Application filed May 1, 1893. Serial No. 472,614. Term of patent 3½ years.

To all whom it may concern:

Be it known that I, ADOLPH PETZOLD, a citizen of the United States, residing in the city of Philadelphia, State of Pennsylvania, have 5 invented and produced a certain new and original Design for a Rug, of which the following is a full, clear, and exact description, reference being had to the accompanying drawing, forming a part of this specification.

10 My invention relates to a design for a rug and will be clearly understood by reference to the accompanying drawing illustrating the same.

15 The leading and distinguishing features of the design in question are the diamond-shaped panel, slightly to one side of the center, showing at the angular base of the panel a body of water with an ancient Spanish vessel float-

ing thereon; and to one side of the panel, the figure of a man representing Columbus, holding in one hand a spear and in the other hand a sword. The corners and other spaces on the rectangular ground-field are filled in with floral decorations and cross emblems, substantially as shown. 20

I claim—

25 The design for a rug substantially as shown and set forth.

In testimony whereof I have hereunto affixed my signature this 27th day of April, A. 30 D. 1893.
